UNITED STATES PATENT OFFICE.

STANISLAUS VON WISZCEWSKY, OF NEW YORK, N. Y.

FLYING-MACHINE.

No. 890,483.

Specification of Letters Patent.

Patented June 9, 1908.

Application filed June 26, 1907. Serial No. 380,892.

To all whom it may concern:

Be it known that I, STANISLAUS VON WISZCEWSKY, a subject of the German Emperor, residing at New York, in the county of New York and State of New York, have invented new and useful Improvements in Flying-Machines, of which the following is a specification.

This invention relates to flying machines and has for its object a device of simple and cheap construction and readily controlled and easily operated as will be more fully described in the following specification, set forth in the claims and illustrated in the drawings accompanying this application where it will be seen that the same reference characters are used to designate the same parts in the various views.

Figure 1 is a perspective view of my improved flying machine. Fig. 2 is a front view of same. Fig. 3 is a side elevation of same.

For the purpose of making a safe and easy start the machine and its operating mechanism are mounted on a platform 5 provided with wheels 6 to render it portable and an engine or motor of sufficient size is inclosed in the housing 7.

Arising from the platform 5 is an upright 8 forked at the lower part and carrying near its upper end a horizontal shaft 9 braced by means of the stays 10 from the platform and the upright, and hinged on this shaft are lateral arms 11 whose outer end are connected 35 with the shaft 9 by means of braces 12.

The rear end of the shaft 9 carries the tail 13 which is made up of a cross piece 14 connected with the shaft by wire braces 15 and covered with silk or some similar light material and which is triangular in shape.

The arms 11 are provided with certain parts to be hereinafter described and which constitute the wings of the machine and these wings are oscillated by means of sectors 16 whose centers are the hinged ends of the arms 11 and they carry on their curved faces ropes or cords 17 and 18 which are connected with a crank arm 19 on a short shaft supported within the fork 20 at the base of the upright 8. This short shaft carries a sprocket wheel 21 and on its other end a crank arm 22 and to the latter is connected the cords or ropes 23 whose outer ends are secured to the upper ends of the segments 16.

The sprocket wheel 21 is driven by means of a sprocket wheel 22 on the driving shaft

23' of the motor and through the medium of a chain 24. The motor shaft is thrown in and out of operation by means of the clutch 25 so that the machine may be started or stopped instantly at the will of the operator and speed moderating devices may also be used at this point. One of the members of this clutch is secured to the hollow motor shaft while the other member is secured to 65 the shaft 23' which passes through the hollow shaft and is coupled with the hollow shaft when the two members are locked together.

The wings are made up of strips 26 of silk, paper or similar material hung from rods 27 which are stretched from the horizontal shaft 9 to the braces 12 and on the upward stroke of the wings these strips or flap, in consequence of the resistance of the air, 70 hang vertically, but on the downward stroke of the wings and forward movement of the machine they assume a horizontal position, supported and retained by each other and the adjacent rods 27. In order to give these 80 strips and the entire ring more rigidity cross rods 28 are arranged parallel with the shaft 9 and secured to the arms 11 and braces 12. These rods 27 and 28 may be fine wire as the strain put upon them is very 85 limited and only sufficient to carry the flaps and resist their upward movement.

As will be seen in the drawings the tail is immovable and in the upward movement of the machine the air above the tail offers 90 enough resistance to same to depress it while the oscillation of the wings tends to elevate the whole machine but the depression of the tail throws the upright out of perpendicular and the platform forward maintaining the 95 necessary equilibrium in the machine. The wheels on the platform not only act as a ready means for transporting the machine but are useful in starting the machine and permitting it to leave the ground but render 100 it more safe in landing when it permits the machine to run over the ground until finally stopped. The oscillating movement of the wings alternately open and close the flaps 26 and each stroke elevates the machine to a 105 higher point and when descending the wings are allowed to remain stationary when the machine, in consequence of its weight, will slowly descend. Pulleys 27 are provided, whenever needed, to ease the movement of 110 the operating cords.

All the parts are necessarily constructed

of the lightest material and it will be observed that the parts are few and substantial.

It is obvious that various modifications of the arrangement and construction of the various parts may be resorted to without departing from the essential features above described.

What I claim as new and desire to secure by Letters Patent is:

- 10 1. In a flying machine the combination with a platform having wheels and carrying a motor, of an upright, a lateral stationary shaft carried by the upright, oscillating wings on the shaft, and means connected with the motor for operating the wings.
- 15 2. In a flying machine, the combination with a movable platform, of a motor, a forked upright, a lateral stationary bar or shaft, a tail at end of same, wings hinged to the bar, and means connecting the motor with the wings to cause them to oscillate.
- 20 3. In a flying machine, the combination with a forked upright carried by a movable platform, of a motor on the platform, a substantially horizontal shaft carried by the upright, stays bracing the upright and shaft, oscillating arms on the shaft, a tail on the shaft, and means connecting the arms with the motor so they may be oscillated on the
- 25 shaft.
- 30

4. In a flying machine, the combination with a platform having wheels, of a forked upright, of a motor, a cross bar or shaft, a tail, arms carrying swinging flaps or sections, segments on the arms, a crank arm operated by the motor, cords connecting one of the crank arms with the arms to swing them downward, and cords connecting the arms with the other crank arm to swing them upward.

5. In a flying machine, the combination with a platform having means for moving same along the ground, of a motor on same, a forked upright, crank arms driven by the motor and carried by the fork, a lateral shaft carried by the upright, hinged arms carried by the shaft, cords connecting the crank arms with the arms so as to oscillate them, braces connecting the ends of the arms with the shaft, rods parallel with the arms and strung between the braces and the shaft flaps suspended from the said rods, and supporting rods connecting the arms with the braces and supporting the flap cords.

In testimony whereof I affix my signature in presence of two witnesses.

STANISLAUS VON WISZCEWSKY.
